UNITED STATES PATENT OFFICE.

KENNETH GRAY FISHER, OF TACOMA, WASHINGTON.

DESIGN FOR A SIGNBOARD FOR WEIGHING-SCALES.

59,001.

Specification for Design.

Patented Sept. 13, 1921.

Application filed January 20, 1921. Serial No. 438,756. Term of patent 14 years.

To all whom it may concern:

Be it known that I, KENNETH GRAY FISHER, a citizen of the United States, residing at Tacoma, in the county of Pierce and State of Washington, have invented a new, original, and ornamental Design for Signboards for Weighing-Scales, of which the following is a specification, reference being had to the accompanying drawing, forming part thereof.

The figure is a perspective view of a sign board constructed in accordance with this invention.

I claim:

The ornamental design for a sign board for weighing scales, as shown.

KENNETH GRAY FISHER.
